UNITED STATES PATENT OFFICE.

FRED D. HOLDSWORTH, OF CLAREMONT, NEW HAMPSHIRE, ASSIGNOR TO SULLIVAN MACHINERY COMPANY, A CORPORATION OF MASSACHUSETTS.

COMPRESSOR MECHANISM.

Application filed September 12, 1924. Serial No. 737,228.

My invention relates to compressor mechanisms.

An object of my invention is to provide an improved compressor mechanism. A further object of my invention is to provide an improved compressor of the portable type. Still another object of my invention is to provide an improved wheel mounted compressor mechanism capable of travelling under its own power to and from its points of utilization and adapted to operate from a trackway. A still further object of my invention is to provide an improved wheel mounted compressor mechanism adapted to be propelled directly from the compressor driving motor and having improved controlling mechanism therefor. Still another object of my invention is to provide an improved portable compressor mechanism wherein the driving motor therefor is adapted to selectively drive the compressor when loaded or to propel the same relative to a trackway when the compressor is unloaded. A still further object of my invention is to provide an improved compressor mechanism mounted on a wheeled truck wherein the driving motor is adapted when desired to simultaneously drive said compressor when loaded and to propel said truck. These and other objects and advantages of my invention will, however, hereinafter more fully appear.

In the accompanying drawings I have shown for purposes of illustration one form which my invention may assume in practice.

In these drawings,

Fig. 1 is a plan view of my improved portable compressor mechanism.

Fig. 2 is a side elevational view of Fig. 1.

Fig. 3 is a front end elevational view of Figs. 1 and 2, the view being partially broken away to facilitate illustration.

Fig. 4 is a transverse sectional view through my improved controlling mechanism, the view being taken substantially on line 4-4 of Fig. 1.

In this illustrated form of my invention I have shown a portable compressor mechanism especially adapted to use in a mine which comprises a truck frame 1 having depending axle boxes 2 suitably secured thereto in which axles 3 are journaled. Wheels 4 are suitably secured to the axles 3 and are adapted to move relative to a trackway, not shown, in a well known manner. A base or

supporting frame 5 is suitably secured to the truck frame 1 by means of intermediate supports or brackets 6 bolted at 7 to the truck frame.

A compressor, generally designated 8, is suitably secured to the base 5 and comprises a frame 9 which carries a compressing cylinder 10 at its forward end in which a piston, not shown, is reciprocable and adapted to be driven through suitable power connections from a crank shaft 11 suitably journaled within the rear end of the frame 9. A reversible driving motor 12 is secured to the base 5. The motor 12 may be of any suitable type but herein is of the electric type. It derives its power from a cable 13 which is adapted to be wound upon a cable reel 14 suitably supported on the rear end of the truck frame 1, and a cable 15 connected to suitable plug and slip ring connections 16 carried by the reel from which the cable 15 leads to the main line switch and reversing mechanism in the control box 17. The motor 12 is also provided with a starting box 18. The armature shaft 19 of the motor has suitably secured thereto a spur pinion 20 which meshes with a large combined internal gear and flywheel secured in any suitable manner to the crank shaft 11. A stationary guard 21 covers this flywheel. The cylinder 10 discharges air under pressure through a pipe connection 22 suitably connected to a receiver 23 secured to the base 5 by means of a strap connection 24. The receiver 23 is provided with a suitable discharge connection 25.

A pilot valve, generally designated 26, which is herein of the well known Osborne type, is connected to the receiver 23 by a pipe connection 27 and to inlet valves 28, which may be of any suitable type, of the compressor cylinder 10 through a suitable pipe connection 29. A three-way valve 30 is inserted between the pilot valve 26 and the pipe connection 29, the third of its ports being connected to pipe 32. It will herein be noted that when a predetermined pressure has been reached in the receiver 23 the pilot valve 26 automatically opens, admitting pressure through pipe connection 29 to the inlet valves 28, unseating the same and unloading the compressor in a well known manner. When the pressure in the receiver 23 drops a certain amount below this predetermined pressure, the pilot valve 26 auto-

matically closes and the pressure unseating the inlet valves 28 is automatically vented to atmosphere, seating the valves and again loading the compressor. If it is desired to 5 manually unload the compressor the lever 31 controlling the three-way valve 30 is manipulated and the pressure is bypassed from the receiver through the connection 32 to the pipe 29, unseating the inlet valves 28 and 10 unloading the compressor.

The crank shaft 11 of the compressor 8 is provided with a sprocket 33 which is connected by means of a chain 34 with a sprocket 35 suitably secured to a transversely extending sleeve member 36 (see Fig. 4) journaled in bearings 37 and 38 carried by a suitable housing member 39 which is in turn supported by the truck frame 1. The sleeve 36 has keyed thereto, at 40, a clutch member 41 provided with a friction surface 42. Brake shoes 43 are adapted to be expanded to frictionally engage the inner surface 42 of the member 41 by means of a shipper member 44 and toggle links 45, 15 which shipper member 44 has non-rotatable engagement with a member 46 keyed, as at 47, to a transverse shaft 48 disposed within and coaxial with the sleeve 36. The shaft 48 is journaled as in bearing sleeves 49 and 20 50 carried by the sleeve member 36 and has secured thereto at 51 a sprocket 52 disposed at the opposite end of the shaft from the sprocket 35 and which is connected by means of a chain 53 with a sprocket 54 suitably 25 secured to the rear axle 3 of the truck. A chain and sprocket connection 55 connects the front and rear axles 3 in operative driving relation. As illustrated the shipper member 44 is adapted to be actuated by a 30 member 56 and a yoke 57 pivoted at 58 on the side of the truck frame 1. The yoke 57 is adapted to be swung about its pivot by means of an operating lever 59 pivoted at 60 on the housing 39 and a connecting rod 40 61 pivotally connected to the lever and the yoke.

It will herein be noted that the clutch member 41 is provided at its outer periphery with a cylindrical grooved surface 62 which is adapted to be connected by means of a belt connection 63 with a similar cylindrical surface 64 formed on the cable reel 14. The tension on the belt 63 is adapted to be adjusted by means of an adjustable idler 55 pulley 65 operated through link connections 66 by means of a grasping lever 67. The truck frame 1 has a platform 68 suitably secured thereto at its side on which the operator rides during the movement of the 60 compressor mechanism about the mine.

A suitable friction brake mechanism, generally designated 70, is secured to the rear axle 3 and is adapted to be operated through suitable lever and rod connections 71 and a 65 grasping lever 72 pivoted on the rear end

of the truck frame. It is obvious that this brake mechanism may be applied when the compressor is moving relative to a trackway of a steep gradient.

In the operation of my improved portable compressor mechanism it will be observed that the clutch mechanism connecting the truck driving shaft 48 with the crank shaft 11 of the compressor is normally thrown out in the position shown in Fig. 4, the compressor 8 driven from the motor 12 pumping air under pressure from the cylinder 10 through pipe connections 22 to the receiver 23 in the usual manner. It will also be noted that the pilot valve 26 automatically 70 unloads the compressor cylinder 10 when the predetermined pressure is reached within the receiver 23. When it is desired to 75 propel the compressor mechanism about the mine the compressor cylinder 10 is manually unloaded by means of a three-way valve 30 and the by-pass connection 32. The operator then throws the clutch controlling lever 59 downwardly (see Fig. 4) causing the yoke 57 to move to the left, thus causing the 80 brake shoes 43 to frictionally engage the inner surface 42 of the driving member 41 which is constantly rotated through the chain and sprocket connections 35, 34 and 33 from the crank shaft 11 of the compressor 85 which is driven by the driving motor 12. Consequently the shaft 48 is rotated, thus 90 rotating the sprocket 52 and the truck wheels 4 by means of the chain connection 53, causing the compressor to be propelled forwardly 95 relative to the trackway. The switch in the control box 17 may be thrown causing the motor 12 to be reversed, consequently 100 reversing the rotation of the sleeve 36 and the truck wheels 4. It will also herein be noted that the cable reel 14 automatically 105 winds in the cable at this time. It will further be noted that if desired the compressor 110 may be propelled about the mine with the compressor cylinder loaded, fluid under pressure then being discharged from the cylinder to the receiver as the compressor mechanism moves about the mine to different points of use, in such manner as to build up 115 pressure in the receiver by the time the next place is reached.

As a result of my invention an improved portable compressor mechanism is provided which is adapted to be propelled directly from the compressor driving motor. It will also be noted that an improved portable compressor mechanism is provided having improved controlling means therefor and an improved general arrangement of parts which is of an exceedingly compact and 120 rugged character especially adapted to use in a mine.

While I have in this application specifically described one form which my invention may assume in practice, it will be un- 125 130

derstood that this form of the same is shown for purposes of illustration and that the invention may be modified and embodied in various other forms without departing from its spirit or the scope of the appended claims.

What I claim as new and desire to secure by Letters Patent is:

1. In a compressor mechanism, a truck 10 having running gear, a driving motor, reduction gearing, a compressor on said truck including an element driven by said reduction gearing, and driving connections between said element and said running gear.
- 15 2. In a compressor mechanism, a truck having running gear, a compressor on said truck having a drive shaft, a driving motor having a power shaft, means for operatively connecting said power shaft to said drive shaft, and driving connections whereby said drive shaft may drive said running gear.
- 20 3. In a compressor mechanism, a wheeled truck, a compressor on said truck having a crank shaft, a driving motor operatively connected to said crank shaft, and driving connections between said crank shaft and said truck wheels.
- 25 4. In a compressor mechanism, a truck having running gear, a compressor on said truck, a driving motor, reduction gearing connecting said compressor to said motor, and driving connections for said running gear driven through said reduction gearing, said driving connections including a clutch controlling the driving of said running gear through said reduction gearing.
- 30 5. In a compressor mechanism, a truck having running gear, a compressor on said truck having a drive shaft, a driving motor having a power shaft, means for operatively connecting said power shaft to said drive shaft, and driving connections between said drive shaft and said running gear, said driving connections including a clutch controlling the driving of said running gear by said drive shaft.
- 35 6. In a compressor mechanism, a wheeled truck, a compressor on said truck having a crank shaft, a driving motor operatively connected to said crank shaft, and driving connections between said crank shaft and said truck wheels, said driving connections
- 40 including a clutch controlling the driving of said truck wheels by the crank shaft.
- 45 7. In a compressor mechanism, a wheeled truck, a compressor carried thereby, a driving motor for said compressor, and means including a friction clutch for driving the wheels of said truck from said compressor.
- 50 8. In a compressor mechanism, a truck 60 having running gear, a compressor on said truck having a drive shaft, a driving motor having a power shaft, means for operatively connecting said power shaft to said drive shaft, driving connections between said 65 drive shaft and said running gear, and unloading mechanism associated with said compressor whereby the same may be turned over loaded or unloaded during truck drive.
- 55 9. In a compressor mechanism, a wheeled truck, a compressor on said truck having a crank shaft, a driving motor operatively connected to said crank shaft, driving connections between said crank shaft and said truck wheels, and unloading mechanism as- 70 sociated with said compressor whereby the same may be turned over loaded or unloaded during truck drive.
- 60 10. In a compressor mechanism, a wheeled truck, a compressor carried thereby, a driving motor therefor, automatic loading and unloading means for said compressor, manual means for rendering said automatic means inoperative, and operative driving connections between the wheels of said truck 75 and said compressor.
- 65 11. In a compressor mechanism, a wheeled truck, a compressor carried thereby, a driving motor therefor, unloading means for said compressor, and means for propelling 80 said truck from said compressor when the latter is unloaded.
- 70 12. In a compressor mechanism, a truck having running gear, a compressor on said truck, a driving motor, reduction gearing 85 connecting said compressor to said motor, and driving connections for said running gear driven through said reduction gearing including a clutch, said connections being adapted, when said clutch is in, to always 90 drive said running gear when said compressor is driven.
- 75 13. In testimony whereof I affix my signature.

FRED D. HOLDSWORTH.
